CLAIM

The ornamental design for a device for controlling, as shown and described.

DESCRIPTION

FIG. 1 is a front, top and right side perspective view of the device for controlling showing our new design;

FIG. 2 is a bottom, right side and rear perspective view thereof;

FIG. 3 is a left side view thereof;

FIG. 4 is a right side view thereof;

FIG. 5 is a front view thereof; and,

FIG. 6 is a top view thereof.

The broken line showing in the figure drawings is for illustrative purposes only and forms no part of the claimed design.
